CLAIM

The ornamental design for noise canceling headphones, as shown and described.

DESCRIPTION

FIG. 1 is a perspective view showing noise canceling headphones.

FIG. 2 is a front view of noise canceling headphones.

FIG. 3 is a rear view of noise canceling headphones.

FIG. 4 is a top view of noise canceling headphones.

FIG. 5 is a bottom view of noise canceling headphones.

FIG. 6 is a side view of noise canceling headphones; and,

FIG. 7 is a side view of noise canceling headphones.

The broken lines depict environment that forms no part of the claimed design.

The broken lines shown including the mostly rectangular member on the headphone below the folding mechanism in the perspective view of FIG. 1, the front view of FIG. 2, and the rear view of FIG. 3.
